SUPPORTING STAND

Louis B. Berg, Chicago, Ill., assignor to Borg-Warner Corporation, Chicago, Ill., a corporation of Illinois

Application May 12, 1938, Serial No. 207,453

3 Claims. (Cl. 248—146)

This invention relates to supporting stands adapted for supporting receptacles such as, for example, washing machines, cooking utensils, flower pots, etc., and has as its general object to provide a supporting stand which is relatively simple and inexpensive in construction and yet extremely sturdy and durable.

Another object of the invention is to provide a supporting stand, which, in addition to the foregoing characteristics, comprises an annular upper region for receiving an article to be supported, said annular upper region tapering downwardly into a plurality of spaced supporting legs, the entire stand being formed of sheet metal without any wastage.

Other objects, the advantages and uses of the invention will become apparent after reading the following specification and claims, and after consideration of the drawing forming a part of the specification, wherein:

Fig. 1 is a side elevation of a stand embodying the invention, with a supported receptacle indicated in broken lines;

Fig. 2 is a perspective view of one of the sections of the stand;

Fig. 3 is a plan view of a series of blanks for forming the sections of the stand, arranged in the relation that they assume when forming part of a strip of the sheet metal stock from which they are formed; and

Fig. 4 is a partial side elevation of a modified form of the invention.

As an illustrative embodiment of one form in which the invention may be embodied, I have shown in the drawing, a stand adapted to support a washing machine, indicated in broken lines in Fig. 1 by the reference numeral 10.

The supporting stand comprises an annular upper region, indicated generally at A, adapted to receive the lower region 11 of the receptacle 10, and to support the receptacle by the engagement of its upper edge 12 with a shouldered portion 13 separating the bottom portion 11 from the upper region of the receptacle.

The lower region of the stand comprises a plurality of spaced legs B, formed integrally with the annular upper region A.

In the preferred form of the invention shown in Fig. 1, the stand is comprised of a single sheet 50 of metal, shown in blank form in Fig. 3, which is formed from a single strip or sheet of material, somewhat wider than the height of the stand. The single strip of material is lanced to form a pair of blanks, or successive pairs of blanks C 55 and D as shown in Fig. 3. Each blank includes

a continuous web portion A', adapted to form the annular upper portion A of the stand, and a plurality of spaced leg-forming portions B'. Each of the leg-forming portions B' comprises a narrow end portion 14', adapted to form the leg proper 14 of the completed stand, and a trapezoidal intermediate portion 15', joined to the web portion A' by a rectangular portion 16'.

In the sheet of material from which the blanks C and D are formed, the end portions 14' of one blank lie between the rectangular portion 16' of the other blank, and the trapezoidal portions 15' lie adjacent each other, diverging in opposite directions alternately as shown. Thus, all of the sheet of material is used, without any wastage.

In the formation of the stand, the leg blanks B' are die-formed to substantially the shape shown in Fig. 2. The end portions 14' are converted into substantially tubular form, and the trapezoidal portions 15' are formed to spathe shape as shown in Fig. 2.

The blank is then rolled to form the web portion A' and the rectangular region 16' into annular and arcuate form, respectively, the spathe-shaped portions 15 changing shape somewhat to conform to the changing shape of the rectangular portion 16'.

In the completed stand, a projected end 17 of the web portion A' is welded or otherwise suitably attached at 18 to the other end of the web portion A' in order to form the completed annular portion A.

The spaces formed between the rectangular portions 16' by the cutting out of the end portions 14' of the complementary blank provide, in the finished stand, spaces 19 between the legs B so that the stand has a plurality of legs that are completely spaced apart from their lower to their upper extremities.

In the modified form of the invention shown in Fig. 4, the stand is formed of a plurality of separate sections, blanked from a strip of material exactly the same width as the height of the stand. In the blanking of these sections, they may be arranged in the strip of stock, in the same manner as the leg sections B' are arranged in Fig. 3, the web portions A' being omitted and the edges of the strips of stock corresponding with the end edges of the end portions 14'. The rectangular portions 16' are welded together, end to end, as at 20 to form the annular receiving portion A.

The spathe-shaped portions 15 joining the legs 14 to the annular portion A are exceedingly sturdy and rigid, and the same is true of the 55

arcuate portions 16. Thus, a very sturdy construction is provided at a minimum of expense.

I claim:

- 5 1. A supporting stand formed of a single blank of sheet metal including a web portion forming an annular upper portion of the stand and a plurality of leg portions, said leg portions being of maximum width where they join the web portion and tapering to minimum width at their ends, and the spaces between the leg portions in the blank being substantially identical in shape to the leg portions themselves.
- 10 2. A supporting stand comprising an annular upper region adapted to receive a tub or the like,

and a plurality of supporting legs therebelow, all formed of a single blank of sheet metal in which the leg portions are identical in shape to the spaces separating said leg portions.

3. A supporting stand comprising a cylindrical 5 upper region adapted to receive a tub or the like, and a plurality of supporting legs therebelow, all formed of a single blank of sheet metal in which the leg portions converge in width towards their ends and the spaces between said leg portions 10 diverge in width towards their ends and are of the same shape as said leg portions.

LOUIS B. BERG.
